CLAIM

The ornamental design for a touch screen case, as shown and described.

DESCRIPTION

FIG. 1 is a front, top perspective view of a touch screen case, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the touch screen case, shown in an environment of use;

FIG. 10 is another perspective view of the touch screen case, shown in environment of use; and,

FIG. 11 is an enlarged view of detail “11” identified in FIG. 1.

The dashed broken lines in the figures illustrate portions of the touch screen case. The broken line showing of environment in FIGS. 9 and 10 depicts environment for the touch screen case. the dash dot dash broken lines in FIGS. 1 and 11 are for the purpose of illustrating the enlarged view indicators. None of the broken lines form part of the claimed design.
